LOUIS EMILE COURTIN, OF PARIS, FRANCE.

CLOCK STRIKING MECHANISM.

SPECIFICATION forming part of Letters Patent No. 503,310, dated August 15, 1893.

Application filed July 20, 1892. Serial No. 440,604. (No model.)

To all whom it may concern:

Be it known that I, LOUIS EMILE COURTIN, clockmaker, a citizen of the Republic of France, residing in Paris, France, have invented certain Improvements in and Relating to Clock-Movements, of which the following is a specification.

My invention relates to clock movements, and it consists in so constructing and combining the striking mechanism that at the half hours the clock will repeat the number previously struck but on a different bell or gong, so as to distinguish the half hour strike from the hour by the difference in the tones or sounds of the bell or gongs.

My improvements can be applied to existing clock movements and in the accompanying drawings I have shown it applied to the well-known Courtin clock movements.

In the accompanying drawings, Figure 1 is the front view of a clock-movement showing parts of the striking mechanism. Fig. 2 is a side view of the said movement, showing the two bells in section. Fig. 3 shows separately the part designed to act upon the arbor. Fig. 4 represents the hammer having a double action.

The arbor *a* which carries the hammer *b b'* is mounted in the two disks *A* and *A'* of the clock movement. It is subjected like the arbors heretofore used to the action of a spring *r* designed to move it back to its original position after the rotation, and it is moreover adapted to be displaced longitudinally under the action of a cam *c* with which its extremity is always in contact, by reason of the pressure exerted by a spring *r'* acting upon its other extremity. This cam appertains to a double lever pivoted at *o*, the arm *d* of which is encountered and oscillated by a pin *e* fixed upon one of the wheels *f* of the dial train, which on its opposite face possesses two diametrically opposite pins *13, 13*, at equal distances from the center designed to act upon the arm 1 of the bell mechanism at each half hour. The usual rack 14 always acts in combination with a scroll wheel 9 which limits its fall according to the hour to be struck. The pivoted arm 7 which carries the rack 14 is normally raised so that the lowest tooth of the rack 14 rests upon the upper end of the lever 15. When one of the pins 13, comes in

contact with the arm 1 of the forked lever 1, 2, it raises the latter, which in turn raises the lever 15 by acting on the pin 3 on this lever 55 15. A lever 5 fixed on the same axis 4 with the lever 15, is, at the same time, moved out of the path of a pin 6 on the wheel 12 carried by the shaft 17 of the striking train. The striking train starts, but is immediately 60 stopped by the projection 10, on the arm 2, which projects into the path of a pin on one of the wheels of the striking train in the ordinary way. At the time the lever 15 is raised out of the way of the rack 14, this rack 65 drops—the extent of the dropping being limited by an arm 8 on the arm 7 coming in contact with the scroll wheel 9, which limits the extent of its fall according to the hour to be struck. When the pin 13 passes the arm 1, 70 the lever 1, 2 drops to its normal position thus freeing the striking mechanism from the projection 10. The striking train now running, the arm 16 on the shaft 17 raises the rack 14 one tooth at each revolution, the rack being 75 prevented from falling back by the lever 15 which engages in the teeth of the rack. When the arm 16 has raised the rack until its lowest tooth is above the lever 15, this lever 15 drops under the lowest tooth of the rack, 80 thus turning the pivot 4 sufficient to cause the arm 5 to come into the path of the pin 6 which arrests the motion of the striking train. It will thus be seen that the construction and operation of the striking mechanism are similar 85 to those of the usual Courtin movement, which strikes one at each half hour, except that by placing the pins 13 equidistant from the center of the wheel *f* and in proper relation to the scroll-wheel 9, and graduating the latter, I am enabled to have the hour numbers automatically repeated at the half hours. The special hammer of the bell mechanism strikes one or the other of the bells *T* and *T'* which gives a different sound. The hours are 90 struck upon the bell *T*, while they are repeated at the half hours by means of the bell *T'* giving a different sound. This effect is produced by the displacement of the arbor *a* which moves the active part of the hammer 100 either opposite to the bell *T* or the bell *T'*. The double arrangement of the hammer is such that when its part *b* strikes the bell *T*, the part *b'* will miss the bell *T'*, and vice versa.

It is evident that the advantage of my system lies not only in the repetition of the hours at the half-hours by a bell giving a different sound, but also, and more especially in the 5 production of this effect with a device of the greatest simplicity.

I may apply my invention to all kinds and sizes of clock-movements and combine it with any kinds of bells.

10 I claim as my invention—

1. In striking clocks, the combination with the striking mechanism of means for automatically repeating the hour numbers at the half hours, and means for sounding a bell or 15 gong at the half hours different from that sounded at the hours, all substantially as described.

2. In striking clocks, the combination of two bells and one hammer, with means substantially as described for automatically repeating the hour numbers at the half hours, and means for shifting the hammer from one 20 bell to the other, substantially as and for the purpose set forth.

25 3. In striking clocks, the combination of two bells, and an arbor carrying the hammer, with a lever provided with a cam at one end adapted to move the said arbor longitudinally

and a pin on one of the dial wheels adapted to act upon the said lever, all substantially 30 as and for the purposes set forth.

4. In striking clocks, the combination of the rack 14 and mechanism for maintaining the rack out of the position it would naturally take, with two diametrically opposite pins on one of the wheels of the dial train and equidistant from the center of the wheel and adapted to act on the said mechanism to release the rack every half hour, all substantially as set forth. 35

40 5. In striking clocks, the combination of the two bells and one hammer, with two diametrically opposite pins on one of the wheels of the dial train and equidistant from the center of the wheel, and adapted to act alike at each half hour on the striking mechanism, and means for shifting the hammer from one bell to the other, substantially as and for the purposes set forth.

50 In testimony whereof I have signed my name to this specification in the presence of two subscribing witnesses.

LOUIS EMILE COURTIN.
